UNITED STATES PATENT OFFICE.

WLODZIMIERZ MISIAK, OF NEW YORK, N. Y.

DUMB-WAITER SIGNAL.

Application filed February 21, 1921. Serial No. 446,658.

To all whom it may concern:

Be it known that I, WLODZIMIERZ MISIAK, citizen of the United States, and resident of New York, in the county of New York and State of New York, have invented certain new and useful Improvements in Dumb-Waiter Signals, of which the following is a specification.

This invention relates to dumb waiters, having more particular reference to a signal system adapted for use in connection therewith.

The invention has for an object to provide a novel arrangement and construction of parts whereby a general signal may be given in the apartments on the different floors when the dumb waiter is moving either up or down or whereby a signal may be given which would only be audible on any floor of which the door leading to the dumb waiter shaft was open.

For further comprehension of the invention, and of the objects and advantages thereof, reference will be had to the following description and accompanying drawings, and to the appended claims in which the various novel features of the invention are more particularly set forth.

Fig. 1 of the drawings is a vertical elevational view showing the application of the invention to a dumb waiter, the dumb waiter shaft being shown in vertical section.

Fig. 2 is a plan view of the variable contact maker carried by the dumb waiter car.

Fig. 3 is a side view thereof.

Fig. 4 is a front view thereof.

Fig. 5 is an enlarged detail sectional view on the line 5—5 of Fig. 3.

Fig. 6 is a top plan view of the dumb waiter with the battery and contact maker mounted thereon.

Fig. 7 is an enlarged detail section on the line 7—7 of Fig. 3.

Fig. 8 is a front view of the dumb waiter equipped as in Fig. 6.

Fig. 9 is a side view thereof.

Fig. 10 is an enlarged fragmentary front elevation of the track carrying the fixed contacts.

In the drawings 10 indicates a dumb waiter shaft which extends upward past the different floors 11 of the apartment house or other building in which the dumb waiter is located. The dumb waiter car is shown at 12 and may be operated by the usual ropes

13, the parts already referred to being of any suitable or usual construction, the dumb waiter shaft having the usual openings 14 communicating with the respective floors of the building.

According to my invention I provide in the dumb waiter shaft a vertical track 17 upon which are a number of contact members located adjacent each floor of the building. These fixed contacts comprise, for each floor, a pair of vertically spaced, relatively wide contact strips 20, 20' having on opposite sides thereof the relatively narrow contact strips 21, 21', these contacts being located adjacent the openings 14.

Mounted on the top of the dumb waiter is a guide base 23 on which is slidably mounted a plate 24 having a bearing ear 25 at one end. This plate is here shown as secured to the base by means of a wing nut 26 threaded on a screw 27 fixed to the base 23 and projecting up through a slot 28 in the plate 24. Pivoted at its lower end as at 29 to the bearing ear 25 is a post 30 having a lever 31 fulcrumed as at 32 to the upper end thereof, the lever being fulcrumed between its ends and having one arm formed in two diverging forks 31' and 31^a. This lever 31 is adapted to be held in different vertically adjusted positions by a link 34 connected at one end to the unforked arm thereof and having its opposite end longitudinally slotted as at 35 to receive a screw 36 projecting from the post, a wing nut 37 being threaded on said screw and clamping the link to the post.

The arm 31' of the lever 31 is formed with a yoke-like extension in which is journaled a single roller 40, this roller being suitably insulated as at 41, the length of this roller corresponding to the distance between the outer edges of the fixed contact strips 21 or 21' with which it is adapted to engage.

The arm 31^a of lever 31 also has a yoke-like extension upon which is journaled a pair of rollers 42 each of which is insulated as at 43, these rollers being laterally spaced so as to engage the centre contact strips 20 or 20' but not touch the side contact strips 21, 21'. A pair of flat springs 44 are secured at one end by screws 45 to the plate 24 and press the post 30 toward the track 17.

Mounted upon each of the different floors is a bell 47 adapted to ring when the contact strips 21 or 21' adjacent the respective

floors are bridged. The wiring connections to these bells are in parallel and comprise the two main wires 48 and 49 leading from a suitably placed battery 50. From the 5 wire 48 branch wires 51 lead to the contact strips 21, 21' on one side of the central strips 20 and from the contact strips on the other side of such central strips wires 52 lead to one terminal of the bell 47, the other 10 terminal of which is connected to the main wire as indicated at 53.

Mounted on the car 12 are a bell 55 and a battery 56, which are connected by a lead 57 whose opposite ends are connected to the 15 respective rollers 42, as indicated in Fig. 5, the roller spindles 42' being extended to form binding posts and provided with binding nuts 58.

By adjusting the lever 31 to either the 20 full line or dotted line position shown in Fig. 3 the single roller 40 or the pair of rollers 42 may be brought to bear on the track 17. When the single roller is bearing on the track the contacts 21 or 21' will be 25 bridged as the car 12 comes adjacent the different openings 14 and the bells 47 on the floors will be caused to ring. If, however, the pair of rollers 42 are bearing on the track the circuit to the bell 55 carried by 30 the car 12 will be closed as the car comes adjacent each opening 14 by reason of the contact 20 bridging said rollers. By providing the vertically spaced sets of contacts 35 adjacent each opening 14 the signal is given as the car moves either up or down while the signal ceases operation when the car is at rest adjacent the opening, in which position the contact element on the car is between the spaced sets of fixed contacts.

40 In the use of the dumb waiter tenants on any floor expecting the delivery of goods may leave the opening to the dumb waiter shaft unclosed, the person operating the dumb waiter then setting the signal device 45 so that the bell on the car will sound. If goods such as milk are to be delivered to all the floors the signal device is set to cause the bells 47 on said floors to sound.

Having thus described my invention what 50 I claim as new and desire to protect by Letters Patent of the United States is as follows:

1. In a dumb waiter, a shaft vertically intersecting the different floors of a building, signals on the respective floors, a car, a signal carried by the car, and selective means whereby either of said signals may be caused to operate as the car comes adjacent the respective floors, said means including 55 a track in said shaft, spaced contacts on said track, and a forked arm pivoted on the car and means for shifting said forked arm to

bring either branch thereof into engagement with said track.

2. In a dumb waiter, a shaft, a car in said shaft, a track in said shaft, groups of contact strips on said track, each group comprising a central strip and a pair of side strips, a signal carried by said car, a series of fixed signals, and means carried by the 65 car whereby a circuit may be closed either through said centre strip and the car signal, or through the side strips and a corresponding fixed signal.

3. In a dumb waiter, a shaft, a car in said 70 shaft, a track in said shaft, groups of contact strips on said track, each group comprising a central strip and a pair of side strips, a signal carried by said car, a series of fixed signals, and means carried by the 75 car whereby a circuit may be closed either through said centre strip and the car signal, or through the side strips and a corresponding fixed signal, said means comprising a forked arm one branch of which carries a 80 single roller, and the other branch a pair of insulated rollers.

4. In a dumb waiter, a shaft, a car in said 85 shaft, a track in said shaft, groups of contact strips on said track, each group comprising a central strip and a pair of side strips, a signal carried by said car, a series of fixed signals, and means carried by the 90 car whereby a circuit may be closed either through said centre strip and the car signal, or through the side strips and a corresponding fixed signal, said means comprising a forked arm one branch of which carries a 95 single roller, and the other branch a pair of insulated rollers, a pivoted post on which 100 said arm is mounted, and a slotted link device for adjustably positioning said arm with respect to said post.

5. In a dumb waiter, a shaft, a car in said 105 shaft, a track in said shaft, groups of contact strips on said track, each group comprising a central strip and a pair of side strips, a signal carried by said car, a series of fixed signals, and means carried by the 110 car whereby a circuit may be closed either through said side strips and the car signal, or through the centre strip and a corresponding fixed signal, said means comprising a forked arm one branch of which carries a 115 single roller, and the other branch a pair of insulated rollers, a pivoted post on which 120 said arm is mounted, and a slotted link device for adjustably positioning said arm with respect to said post, and a spring pressing said post toward the said track.

Signed at New York, in the county of New York, and State of New York, this 16th day of February, A. D. 1921.

WLODZIMIERZ MISIAK.
